UNITED STATES PATENT OFFICE.

LEWIS MILLER, OF AKRON, OHIO.

GRAIN-BINDING HARVESTER.

SPECIFICATION forming part of Letters Patent No. 341,675, dated May 11, 1886.

(Application filed May 6, 1884. Serial No. 130,557. No model.)

To all whom it may concern:

Be it known that I, LEWIS MILLER, of Akron, county of Summit, and State of Ohio, have invented a new and useful Improvement in 5 Grain-Binding Harvesters, of which the following is a full, clear, and exact description, reference being had to the accompanying drawings, making part of this specification.

My invention relates to that class of grain-binding harvesters in which the grain is bound on an inclined elevating-table interposed between the platform-carrier and the path of the driving-wheel, and more particularly to the arrangement of the devices or mechanisms for 10 taking the grain from the carrier at the foot of the inclined table and moving it upward thereon to the compressing or packing and binding mechanisms; and to this end the invention consists, first, in the combination, with 15 the binder-table, located as described, and with mechanisms for packing and binding the grain thereon, of a picking or gathering mechanism composed of elliptically-moving picker-fingers operated from beneath the inclined table from 20 a crank-shaft located between the packer-shaft and the inner end of the platform-carrier, in a novel arrangement of the butter-shaft and of the means for supporting the same, whereby it is adapted to be driven from the picker- 25 shaft located beneath the binder-table, as described, and to be supported from the platform-frame; and in the combination, with the heel end of the reciprocating sickle-bar, of pivoted and folding angular or L-shaped teeth or 30 fingers upheld in operative position by springs, and adapted to assist in moving the butts of the grain inward to the action of the pickers and butter, and to fold down and pass outwardly beneath the butts of the grain in the 35 40 outward throw of the sickle-bar, as herein-after explained.

In the accompanying drawings, Figure 1 is plan view of the drive-wheel end of a harvesting-machine embracing my improvements, 45 with the binder-table removed and parts broken away to show the arrangement of other parts. Fig. 2 is a front elevation, also with parts broken away, showing the arrangement of the pickers or gatherers relative to the 50 packers, and the butter and folding fingers on the knife-bar. Fig. 3 is a rear view showing the arrangement of the pickers or gatherers and

means for actuating the same, and Fig. 4 is a view of the folding teeth on the heel end of the knife-bar, enlarged.

The frame-work of the machine and the manner of connecting the same with the main drive-wheel, as shown in the drawings, are the same as in another application filed here-with, dated May 6, 1884, Serial No. 130,556, 55 and being therein fully described, it is unnecessary to describe the same in detail here, as they may be varied so long as the features of general arrangement or relation of parts herein referred to are retained.

The binder-frame and inclined elevating binder-table, together with the mechanism for binding the grain thereon, are mounted upon the inner end of the main or platform frame adjacent to the drive-wheel A, and between 60 said wheel or the path thereof and the inner end of the platform-carrier B.

Motion is imparted to the various operative parts of the machine—from the main drive-wheel in the present instance—through the 65 medium of a spur gear or rim, A', fast on the drive-wheel and meshing with a pinion, a, on a secondary transverse shaft, a', mounted in suitable bearings in a binder-frame support or chair, C, and provided with a bevel wheel or 70 pinion, a'', engaging and driving a bevel-wheel, a'', on the first longitudinal and main binder-gear shaft, D, from which motion is communicated to the various operative parts of the machine, to the binding and packing mechanisms, 75 in a manner and under an arrangement similar to that described in Letters Patent No. 276,448, granted to me April 24, 1883, the shaft D being a crank-shaft, to which the elliptically-moving packers b b, operating from beneath the slotted binder-table E, are attached. The shaft D has a spur-wheel, d, upon it, which 80 meshes with and drives a pinion, d', fast on a crank-shaft, D', from which motion is communicated to the knife-bar, and upon its rear end 85 has a sprocket-wheel, d'', fast upon it, from which, through an endless drive-chain, e, and suitable sprocket-wheels, d''' and d'', (the former fast on the crank-shaft F, actuating the picker or gathering-fingers, and the latter, d'', on the 90 shaft of the inner carrier-roller,) it actuates the inner carrier-roller. The drive-chain moves outward under the sprocket-wheel d'', held up in engagement therewith by an adjustable guiding

and tension sprocket-wheel, d^5 , and thence under and around the wheel d^4 , and serves to give to said sprocket-wheels d^3 and d^4 and their shafts the same direction of rotation that the shaft D has—viz., inward or toward the drive-wheel on their upper faces. The picker-shaft F passes through the rear sill of the platform-frame, or a bearing thereon, near the foot of the inclined binder-table and underneath the same, 10 and is supported in bearing-brackets F', secured to the lower longitudinal sill of the binder-frame, and has cranks f'f', in pairs, set one opposite to the other, formed in it, to which are connected fingers g'g', which curve 15 upward toward their points, and the heel ends of which, extending inward beyond their actuating-cranks, are connected by short pivoted links g² with suitable lugs, g³, on the lower longitudinal bar of the binder-frame or other 20 convenient support. These fingers are so arranged relatively to the inner roller of the platform-carrier as to move up through slots in the binder-table in close proximity to said roller, and serve to pick the grain from the 25 delivery end of the carrier, and by their sweeping elliptical movement to carry the grain upward on the binder-table to within reach of the packers and needle.

To the forward end of the shaft F is secured 30 a beveled pinion, h, which drives a similar gear, h', on the lower end of an upright shaft, H, through which motion is imparted to the butter H. The butter shown is of the slatted endless apron form well known, and the shaft 35 H actuating it, and forming the pivot upon which its upper end is adjusted by any usual or preferred means, is supported in bearings in arms of an upright metallic frame, I, secured by flanges or feet to the front platform- 40 sill, and also, if desired, to a wing or inclined guard, J', formed on the inner shoe, thereby supporting said butter-shaft from below only.

The butter-shaft is provided with a tumbling extension, H², from which, in practice, 45 motion is imparted to the reel in a similar manner to that described in the patent above referred to, or in any suitable manner.

The reciprocating knife or sickle bar K has short upright lugs or ears formed upon or secured to it near its inner end, to which lugs 50 small angular fingers l l are pivoted, with their longer arms, which are adapted to stand in an upright position when the sickle-bar is moving inward and to lie down when the bar 55 is moving outward, curved upward, when in the last-named position, toward their points or ends, for adapting them to catch and be raised by the grain in their inward movement. The short heel ends l' of these angular 60 fingers prevent their long arms passing beyond the upright position when raised by the action of the grain, as described. The grain behind the long fingers causes the latter to be thrown down in the outward movement of the 65 bar, and a light spring, m, secured to the bar on the outer side of the finger, with its free end overhanging and resting on the short end

l', prevents the grain from catching on said arm in its outward movement, acting as an incline over which the grain rides easily, said spring, by its tension, serving also to assist in raising the long arm or finger in the inward movement of the bar.

Those acquainted with the working of this class of machines are familiar with the fact 70 that the butts of the grain, because of their smooth hard surfaces, tend to drag on the forward sill or finger-bar, and to slip on an ordinary carrier and lag or drop behind the heads, which have no such tendency to slip. 80 This action or tendency renders it important to supplement the action of the carrier and the devices for taking the grain therefrom by some device of the kind last above described, in order to make the butts keep well up with the 85 heads, and thereby insure their being caught and acted upon by the pickers and butter simultaneously with the action of the pickers or gatherers and other elevating devices on 90 their heads for presenting the straw in proper shape to the binding devices.

Having now described my invention, I claim as new—

1. The inclined elevating binder-table located between the platform-carrier and the driving-wheel, and the elliptically-moving pickers or gatherers operating from beneath said table to move the grain from the platform-carrier to and place it upon said table, in combination with the crank-shaft for operating said pickers, located beneath said table, and the vibrating links supporting the heel ends of said pickers, pivoted to a longitudinal rod or bar mounted on and connecting the front and rear horizontal platform-frame sills underneath the binder-table, substantially as described.

2. In a grain-binding harvester, the combination, with the side-delivery platform-carrier, of the inclined elevating binder-table and packers operating in connection therewith, arranged between said carrier and the driving-wheel, elliptically-moving pickers or gatherers operating from beneath said table, a crank-shaft, also located beneath the inclined binder-table, for actuating said pickers for moving the grain from the inner or delivery end of the platform-carrier up to the packers, and butting mechanism geared to and operated from said picker-actuating 110 crank-shaft, substantially as described.

3. The combination, in a grain-binding harvester, of the inclined elevating binder-table and packers operating in connection therewith, interposed between the platform-carrier 125 and the driving-wheel, the elliptically-moving pickers or gatherers operating from beneath said inclined table for moving the grain from the inner or delivery end of the platform-carrier up to the packers, said pickers being actuated by a crank-shaft, also located beneath said table, a butting-mechanism shaft geared to and operated from said picker-shaft, and a supporting-frame in which said butter-shaft

has its bearings, upheld at its lower end through connections with the main platform and binder-frames only, substantially as described.

5 4. In a harvesting - machine, the inclined binder-table interposed between the platform-carrier and the path of the drive-wheel, elliptically-moving pickers or gatherers operating from beneath for moving the grain upward 10 on said table from the delivery end of the platform-carrier to the packing and binding mechanisms, in combination with packing and binding mechanisms and a reciprocating sickle-bar provided at its inner end with the 15 L shaped pivoted and folding fingers for assisting in moving the butts of the grain, substantially as described.

5 5. In a grain-binding harvester, the combination, with the heel end of the reciprocating sickle-bar, of the L-shaped spring-actu-

ated folding fingers pivoted to said bar and adapted to act on the butts of the grain in the inward throw or movement of said bar, and to fold down and pass outward underneath said butts without acting thereon, substantially as 25 described.

6. The combination, with the picker-shaft, located beneath the binder-table at or near the inner end of the platform-carrier, of the butter-shaft geared to and operated from said picker-shaft from below said binder-table, and the tumbling extension of said butter-shaft for actuating the reel. 30

In testimony whereof I have hereunto set my hand this 12th day of April, A. D. 1884. 35

LEWIS MILLER.
